Application November 8, 1948, Serial No. 58,929

23 Claims. (Cl. 197—113)

1

This invention relates to typewriters, and with regard to certain more specific features, to an automatic character repeater for such machines.

Among the several objects of the invention may be noted the provision in a typewriter of an improved automatic character repeating means; the provision of repeating means of the class described which requires no change in the usual operating linkage of machines to which the invention is applied; the provision of a device of the class described which when automatic repeating action is not desired, permits a typewriter conveniently to be used as usual; the provision of a repeating mechanism which is conveniently adaptable by an operator to various exigencies of character repetition with a minimum number of auxiliary operations to be learned, said auxiliary operations being simple and foolproof; and the provision of apparatus of this class which is rapid, reliable, simple and economical in construction, and easy to adapt to present-day typewriter designs. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a plan view of a typewriter embodying the invention;

Fig. 2 is a left-side view of Fig. 1, parts being broken away more clearly to illustrate certain features;

Fig. 3 is a rear elevation, parts being shown in section, the device being set for ordinary operation of the typewriter carriage but wherein the end has been reached of a half-page type-written line to be underlined;

Fig. 4 is a view similar to Fig. 3, except that a preliminary setting has been made of the carriage to starting position for underlining;

Fig. 5 is a view similar to Fig. 4, in which automatic underlining operation is occurring and approaching (without as yet again having attained) the Fig. 3 position;

Fig. 6 is a wiring diagram;

Fig. 7 is a fragmentary detail view of parts of Fig. 2, illustrating a modified key-operating mechanism;

2

Fig. 8 is a modified wiring diagram for the modification shown in Fig. 7;

Fig. 9 is a fragmentary view similar to Fig. 2 but diagrammatically illustrating a modified form of the invention; and,

Fig. 10 is a wiring diagram for the form of the invention shown in Fig. 9.

Similar reference characters indicate corresponding parts throughout the several views of the drawings.

Many times it is desirable when typewriting to repeat a character, for example, an underline character. Where there are a great number of repetitions required, the operation, if manually performed, becomes a great and time-wasting burden upon the operator. By means of the present invention any desired repetition may be performed automatically without destroying the ability to carry it out manually if desired. Moreover, the typewriter to which the invention is applied may be used in the normal manner and the action of automatic character repetition instigated whenever needed. In addition, the automatic operation is such that when the character repetition such as underlining is to be ended at a certain point, such as at the end of a line, no unduly close attention or closely precise timing of manipulations is necessary to cause the underlining and the line to be coterminous.

The invention is described in particular in connection with the repetition of the ordinary underlining bar forming one of the characters on an ordinary typewriter keyboard. This character usually occupies a position on its respective type block requiring the carriage of the machine to be elevated by a usual "shift lock" key. It is to be understood, however, that the invention is applicable to the repetition of any character, whether or not the printing of the character requires the carriage to be shifted up. Thus the invention can be made to repeat any symbol such as the dash, asterisk, period, or any other suitable character.

Referring now more particularly to Figs. 1 and 2 of the drawings, there is shown at numeral 1 the frame of an ordinary typewriter. This frame 1 is mounted upon a hollow base 3. The latter is adapted to house certain driving parts illustrated in Figs. 2 and 3. The frame 1 supports the usual operating keys K, including a capital shift-lock key K—9 for shifting the carriage of the machine vertically to a position to receive capital letter imprints. On the keyboard shown there is also a so-called "Fig" shift-lock key K—7 for shifting the carriage of the machine vertically

to another position to receive imprints of numbers and miscellaneous characters such as brackets, underlining, dashes, etc. On many machines these two shift-lock keys are incorporated into one key, but that circumstance has no bearing on the present invention, since its parts may be associated with the operation of either shift-lock key K-7 or K-9 or a single shift-lock key if used. Moreover it is adaptable to machines wherein no shift-lock key operation is required to bring about printing of the character which it is desired to repeat.

The keyboard also includes the usual space bar B. The typewriter also includes the usual ribbon control mechanism shown in part at numerals 11, and striker arms S, respective ones of which are suitably linked to the respective levers of the keys K. The lever or key bar forming part of one striker-connection is indicated at 19, the particular connection being the one between the key K-1 (carrying the underlining bar index 2) and the striker bar S-1 which moves the underlining type bar slug 4. The typewriter includes the usual main carriage 13, which advances step by step as respective ones of the keys K are depressed in typing.

The carriage 13 may be manually set at any position by means of the usual return lever 15 or release lever 6. The carriage supports a paper backing roll 17. The parts thus far described form the particular background for the invention. It is to be understood that the typewriter additionally includes all of the usual accessories to make it a completely operative machine.

Referring to Figs. 2 and 3, numeral 21 indicates a motor in the base 3 which by a speed-reducing unit including friction wheels 25 and spur gears 27 is connected to a driving crank 23. Thus when the motor is energized, the crank 23 turns at a speed corresponding to the desired rate of automatic character repetition. The crank includes a crankpin 29 which engages in the slot 31 of a lost-motion bar or link 33. The latter extends up through a suitable opening 35 to a pin connection 37 with the selected lever 19 of the key K-1 carrying the index 2 of the character selected for repetition (in this case an underlining dash). The length of the slot 31 is limited in the downward direction, so that as the crankpin 29 traverses the lower arc of its motion circle, the lever 19 will be pulled down to cause the respective striker arm S-1 to go into striking operation just as it would if the lever 19 were operated by the application of finger pressure to its respective key K-1. When the lever 19 is repeatedly operated upon successive rotations of the crank 23 (motor 21 energized), the typewriter spaces in the usual manner, which needs not to be described. Under what circumstances the motor 21 is energized to instigate the repeating effect will be described below.

Attached to the rear of the carriage 13 and movable therewith is a framework 39 (Fig. 2) which includes two opposed rails 41 (Figs. 3-5) forming opposite guides for rollers 43 of a sub-carriage 45. This sub-carriage 45 is formed with two oppositely sloping cam shoes 47 and 49, which may be integral, welded or otherwise attached. The adjacent heel portions of the cam shoes 47 and 49 are spaced apart to form a slot 53 or space for the reception of a detent lever 55. The circumstances under which the lever 55 enters the slot 53 will appear.

Swinging across the slot 53 is a lower arm 57 of a bell crank 59 pivoted to the sub-carriage 45

at 61. A second arm 63 of the bell crank extends upward and carries a lift wheel 65. The pin 67 which forms a rotary support for the wheel 65 also fastens in place a pawl 69. When the detent lever 55 is up in the space 53, the arm 57 is lifted, thus lifting the pawl 69 and wheel 65.

Rigidly attached to the framework 39 is a toothed rack 71 adapted to be engaged by the pawl 69 when the latter drops, as when the detent lever 55 is removed from the space 53. At the time the pawl 69 disengages the rack 71 the lift wheel 65 engages a switch-operating trolley bar 73 which is pivoted at 75 to said frame 39. Since the wheel 65 runs along the bottom of the trolley bar 73, the latter may be vertically moved by the wheel in any position of the sub-carriage 45 relative to the main carriage 13.

The nonpivoted end of the switch-operating bar 73 carries a pin 77 which is guided by a slot 79 formed in a stationary part 81 attached to the framework 39. Attached to the part 81 is a switch 83 having a button 85 adapted to be contacted by the end of the bar 73 when the latter is allowed to drop. Such action closes the switch. Thus it will be seen that the switch 83 may be opened or closed by the lifting or dropping action of the lift wheel 65 in any position of the sub-carriage 45 relative to the carriage 13.

The detent lever 55 is pivoted at 87 to a rigid bracket 89. This bracket is attached to the usual lift parts 91 which cradle the carriage 13. The lift parts are the ordinary ones controlled from keys K-7 or K-9, for setting the carriage 13 into appropriate elevated position. Thus although the bracket 89 may rise and fall with the carriage 13 as it is lifted and lowered by the cradle 91 under action of the keys K-1 and K-9, the bracket 89 does not move laterally with the carriage. Thus the pivoted lever 55 has a fixed location, laterally considered. The lever 55 is normally biased upward by means of a spring 93 reacting from a point on bracket 89. It may be pulled downward by means of a cable 95, guided over a pulley 97 and attached at 99 to an operating lever 101. Thus it will be clear that whenever the space 53 between the cam shoes 47 and 49 comes opposite the lever 55, the latter will, under its upward bias, push up the arm 57, thus lifting the pawl 69 from the rack 71 and lifting the wheel 65. The latter lifts the trolley switch bar 73 to cause the switch 83 to open. This state of affairs is shown in Fig. 3. Under such circumstances, the carriage 13, including the extension parts 39, rails 41, rack 71 and trolley switch bar 73, may be traversed back and forth independently of the sub-carriage 45, which remains anchored due to the interlock between the detent lever 55 and space 53 of the sub-carriage.

In Fig. 6 is shown a circuit diagram for the motor 21. The circuit is connected across suitable line terminals 103, and is completed serially through the motor 21, a normally closed limit switch 105, a normally open push-button switch 107 and the normally open switch 83 which is operated by the trolley switch bar. The normally open push-button switch 107 is located in the position shown at the lower right in Fig. 1. The normally closed limit switch 105 is also shown in Fig. 1. This switch 105 is adapted to be engaged and opened by a finger 109 on the right-hand end of the carriage 13 when the latter is in a left-hand limiting position. This finger is part of a rider 110 which is adjustable in position on a cross bar 112 which forms a part of the main

carriage 13. The finger 109 may be held in any selected lateral adjustment by means of a thumb screw 114 capable of locking the rider to the cross bar at will in any adjusted location.

Operation is as follows:

Normally, the parts are in the conditions shown in Figs. 1, 2 and 3, wherein the carriage 13 may be operated laterally in the usual manner without interference. This lateral operation is relative to the sub-carriage 45, which is held in fixed position by the detent lever 55. The motor 21 is inoperative because switches 83 and 107 are normally open. Thus an operator can use the typewriter in the ordinary manner.

Quite often, particularly in the case of extensive tabulation, it is desired to underline a line of material that has just been finished, the underlining to start where desired, which is usually at the beginning of the line. Assume that a line of typing (half-page length for example only) has just been finished and it is desired to underline that line completely. The page is shown by dotted lines P in Fig. 1. Figs. 1 and 3 show the positions of the parts under such conditions. It will be observed that the main carriage 13, including the framework 39, up to this stage has been moving in the direction of the arrow shown in Fig. 3. This movement has been independent of the sub-carriage 45, which has been held in place by the detent lever 55. The effect of the movement of the main carriage 13 has thus been to determine the relative position of the sub-carriage 45 with respect to the main carriage.

Assume now that the line just written is to be underlined from its beginning. Whether or not the underlining is to start at the beginning of the line or elsewhere is optional. In any event, the operator, prior to returning the carriage 13 to the desired starting point for the underlining, throws rearward the operating lever 101. It will be clear from Figs. 2 and 3 that such action of the lever 101 through pull on the cord 95 will draw the detent lever 55 down from the space 53. This releases the sub-carriage 45 which, because of the interlocking effect of the bar 55 up to this event, has been prevented from moving relatively to the main frame 1.

It will also be observed that the detent lever 55, when it was in the space 53, held up the arm 57 and consequently held the pawl 69 clear of the rack 71 (Fig. 3). This also caused the lift wheel 65 to hold up the trolley switch bar 73 in all positions of carriage 13. Hence when the lever 55 is drawn down (upon action of the lever 101), not only is the sub-carriage 45 released from anchorage with the main frame 1, but it is then connected to the parts moving with the main carriage 13. Therefore, when the operator takes the next step (after moving lever 101) of moving the main carriage to a position for starting the underlining, the state of affairs shown in Fig. 4 will exist. That is to say, the sub-carriage 45, being now free of the detent lever 55 and coupled to the rack 71 by pawl 69, will move with the carriage, maintaining its adjusted position thereon. After a suitable amount of movement of the sub-carriage 45 for clearing the lever 55 from the space 53, the lever 101 may be released by the operator.

The operator finally positions carriage 13 so that subsequent underlining will start where desired. Assume this to be at the beginning of the line in the present example. It will be understood that at any point up to the present event, the operator may have depressed the shift-lock key 75

K-7 to bring about lifting of the carriage to a position wherein the underline character will print when the key K-1 is depressed. It will be understood that elevation of the carriage 13

5 through lift of the cradle parts 91 upon operation of shift-lock key K-7 will not itself cause the detent lever 55 to be pulled down, because the spring 93 has substantial tension. Under these circumstances, lever 55 draws the cord 95 to move the lever 101 into the initial position from which it is operated. A light coil spring 12 biases the lever 101 anticlockwise (Fig. 2) to maintain tension in the cord 95. This bias is not enough to overcome the tension in spring 93. Manual operation of the lever 101 is sufficient to overcome tension in spring 93. Hence it is immaterial whether the operator pushes the shift-lock key K-7 into the elevating position shown in Fig. 2 before or after operation of lever 101.

20 It will be observed that once the lever 55 is out of the space 53, the wheel 65 descends, allowing the trolley switch bar 73 to move down to close the switch 83. This switch closure prepares the circuit of motor 21 (Fig. 6) for final manual closure at push-button switch 107. Thus the next step is for the operator to manipulate the push-button switch 107 and hold it down. The result will be that the motor 21 is energized, which, through the train 25, 27, drives the crank 23 (Fig. 2). This, through the crankpin 29 in slot 31, intermittently pulls down the bar 33. Thus the key bar 19 is intermittently pulled down, with the result that the underlining character is repeatedly typed. The typewriter of course advances space by space just as it would if the key bar 19 were operated repetitiously by hand. The speed of the motor, however, is such that repetitions are automatically accomplished faster than by hand.

40 Thus the parts rapidly move from the position shown in Fig. 4 through that shown in Fig. 5 to that shown in Fig. 3. It will be observed that during this action the sub-carriage 45 rides along with the main carriage 13. Ultimately, the leading cam shoe 49 engages the lever 55 to push it down, so that as the space 53 comes opposite the lever, the lever will be pulled into the space by the spring 93. This lifts the arms 57 and 63 and hence also lifts the wheel 65 to lift the trolley switch bar 73, which opens the switch 83. The switch opens to stop the underlining action exactly at the end of the line, as was automatically predetermined by the positioning of the sub-carriage 45 relative to the main carriage 13 under the circumstances illustrated in Fig. 3. It should be understood that the central position adopted for the carriage 13 in Fig. 3 is only exemplary and other positions for line endings are handled equally well. Starting at the time that the pawl 69 is lifted from the rack 71 the sub-carriage 45 remains anchored with the detent lever 55, but the main carriage 13 may be freely operated back and forth for the further typewriting purposes of the operator. Whenever the operator desires, the repeating action may again be instigated in the manner described.

It will be observed that the switch button 107 needs not to be released at any critical time. It is only necessary that it be held down long enough that the underlining can at least occur up to the end of the line which it is desired to underline. Even though the operator holds down the switch 107 for a greater length of time than necessary, the switch 83 automatically opens at the predetermined time for ending the underlining.

The stopping of the underlining is determined without any conscious presetting upon the part of the operator, the presetting being automatically taken care of by the relative movements between the main carriage 13 and the sub-carriage 45 when the latter is anchored by the detent lever 55 in the Fig. 3 position. This is an important advantage of the invention from the viewpoint of simplifying the operating technique.

If the operator should desire for some reason to continue underlining beyond the point at which automatic underlining ceases, she can continue the underlining manually. If she should want to extend underlining by automatic operation beyond a written line, this could be accomplished by presetting the carriage 13 to the proper point through other means than by typing a line; for example by releasing the carriage in the usual manner from release lever 6 and moving it leftward (viewed from the front).

The purpose of the second cam shoe 47 is to allow the lever 55 to ride into the space 53 from the opposite side. For example, should the operator, instead of moving the carriage in the direction shown in Fig. 4 after depressing lever 55, move it in the opposite direction, it would be necessary that the lever 55 ride into the space 53 over the shoe 47 before the sub-carriage 45 would be reanchored to the frame 1 and become free of the main carriage 13.

It may be noted that as long as the detent arm 55 anchors the sub-carriage 45 to the frame, allowing relative movements between the main carriage 13 and the sub-carriage 45, the sub-carriage registers distance on the main carriage upon movement of the latter. This occurs, for example, during the time that the operator types a line which it is desired to underline. Then by releasing the detent manually, not only is the sub-carriage 45 released from the frame, but it is locked to the main carriage 13 to maintain the registered distance when the main carriage is moved to the proper position for starting the repetitious action (underlining). Then as the repetitious action of the typing mechanism occurs, the predetermined distance is taken up by motion of the sub-carriage 45 (with the main carriage) toward the detent 55. The detent is reached only after the registered distance has been traversed. The embodiment of these principles accounts for the simplicity of the operations required of the operator for bringing the repeater into action.

It may be remarked that no damage can be done to the writing by inadvertent failure of the operator to operate lever 101 after a line has been written, even though she returns the carriage to a starting position for repeating action. This is because if under such conditions she presses the switch 107, the motor 21 will not be energized because the switch 83 will be open. Thus the operator is reminded of the fact that an error has been made and simply runs the carriage back to the end of the line prior to properly manipulating the lever 101. If before running the carriage back again, she were to operate the lever 101 and press the switch button 107, the repeater mechanism would go into operation with the sub-carriage 45 moving farther and farther away from the detent 55 (toward the right in Fig. 2) and would never approach it. This is the reason for the introduction of the limit switch 105. Thus if under the stated conditions she holds down the switch 107 inadvertently until the end of the movement of the

main carriage 13 is reached, finger 109 will contact switch 105 to open it. Naturally, an operator would very quickly learn that the first operation to be performed after the end of a line is reached is to operate the lever 101, then to start the return of the carriage 13 and to release lever 101 before pressing switch 107.

The purpose of making the finger 109 adjustable in position on the carriage 13 is to allow for another function of the machine, which is to provide the operator with means for automatically repeating a character (such as an underline character) out to a fixed margin at the right-hand side of the page, instead of simply to the end of the line that may have been written. After the operator has written a desired line (or before), instead of initially moving the lever 101 to release the sub-carriage 45 from the main carriage 13, she omits this step and returns the main carriage to the position at which she wishes to start the underlining. Obviously, this type of operation causes the sub-carriage to remain fixed relative to the main frame of the machine, thus cancelling out the effect of any predetermined sub-carriage adjustment on the main carriage. Thus the underlining will not cease at the end of the line. Her next step (in this desired contingency), after having returned the main carriage as stated, is to operate the lever 101 and to press the switch key button 107. The result will be that the device will go into automatic repeating (underlining) operation and continue to do so until the adjusted finger 109 strikes the switch 105, after which the device turns off at the predetermined marginal position. The operator can repeat this operation as often as desired on successive lines, thus obtaining a series of character repetitions (underlinings) ending at a preset right-hand margin.

An example of a requirement for this type of operation would be a report, statement or tabulation covering financial or operating reports of a business, railroad or public utility, where many headings, divisions, subtotals and totals are outlined or indicated by lines that end at a common right-hand margin on the paper. Other typing forms requiring this type of automatic operation to an adjustable fixed predetermined margin will suggest themselves.

The circuit shown in Fig. 6 includes sections that are on various relatively moving parts. Obviously, flexible connections can be used for completing the circuit under these circumstances. To simplify the description the appropriate types of connections are not shown, being obvious.

It may be observed that other characters than the underliner shown may be repeated by making the connection between the lost-motion link 33 with the key bar of another one of the keys K. Furthermore, the appropriate character may be one which does not require for application to the paper a depression of the shift-lock key K-7 or K-9. This is because the operation of the device of the invention is the same whether or not the carriage 13 is in lifted position for typing; that is, whether or not the cradle 91 is up or down.

In the above, the motor 21 with appropriate linkage has been described for operating the key K-1. Instead of such a drive, an electromagnetic drive may be employed such as shown in Fig. 7. In this case, an electromagnet 135 is mounted below the key bar 19 by means of an arm 133. An armature 134 is attached to the key bar 19 by means of an arm 133. Thus whenever the electromagnet is energized, the key

bar 19 is drawn down for operation. In order to break the circuit for repetition, a switch 137 is provided. A spring arm 138 of this switch 137 is adapted to be engaged by the armature 134 each time that the latter is drawn down. This opens the switch 137, which is in the operating circuit illustrated in Fig. 8. The other parts of this circuit are as already described, with the exception that the motor 21 is replaced by the coil of the electromagnet 135. Since the switch 137 is normally closed, when the circuit is otherwise closed, the electromagnet 135 is enabled to draw down the armature 134 and operate the key K—I. Each time that the key is depressed, the switch 137 is opened. The operation is repeated until another switch in the circuit is opened. The opening operation of the other switches need not be repeated, since it is the same as already described. It will be understood that the extension 133 may be attached at any convenient point along the bar 19.

It will be understood that the invention as shown in Fig. 2 has been shown as applied to an essentially manually operated keyboard to which is applicable the motor drive 21 for the key K—I or the electromagnetic drive of Fig. 7. As is well-known, many machines on the market today have electromechanically driven keys. Such machines consist essentially of a continuously operating motor driving a continuously rotating servo shaft. This shaft may, for example, drive a rubber roller, and upon initiation of the operation of any key, a tumbler temporarily engages the roller to complete the key action.

In Figs. 9 and 10 is shown diagrammatically how a servo shaft 116 of an electrically operating machine may be used to drive the key K—I. In this case, the motor 21 is eliminated, together with its drive 25. The continuously operating motor for the servo shaft 116 is not shown, being, as above stated, well-known. It will be observed that neither such a motor, nor the servo shaft can be started and stopped without interfering with its other usual functions. Figs. 9 and 10 show how the servo shaft 116 through a selectively operable clutch can be made to operate the key K—I when desired. To shaft 116 at a suitable location is attached a bevel gear 117 which, by means of a bevel gear 118, drives shaft 119 and the driving plate 141 of a magnetic clutch 123. If all the switches of the control circuit shown in Fig. 10 are closed, a current will flow through to the electromagnet 143 of the magnetic clutch, causing it to close in a driven face plate 145. Plate 145 is loosely splined to a shaft 121. Shaft 121 drives bevel gears 125, 127, shaft 129 and the worm gear set 131, which in turn drives gear set 27. In Fig. 10, the coil 143 is illustrated to take the place of the motor 21 in Fig. 6. As the action beyond this point has already been fully described, it need not be repeated here. The opening of any or all of the switches of the control circuit stops the repeating action by deenergizing and opening the clutch 123.

From the above, it will be seen that the invention is not limited to application to manually operated machines but may be applied to electromechanically operated machines as well. The chief difference is that a clutch between the power source (motor) and the key mechanism is opened and closed instead of controlling the motor directly, or a controlled repeating mechanism is attached to cause the necessary type bar to operate repetitiously.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

10 I claim:

1. A character repeating mechanism for a typewriter having on a frame a main carriage and a typing mechanism for the character to be repeated; comprising an electrically controlled mechanism adapted when energized to operate said typing mechanism repetitiously, an energizing circuit for said electrically controlled mechanism, an automatic switch in said circuit, a sub-carriage, a latch mechanism on the sub-carriage for attaching it to or detaching it from the main carriage for movement therewith or relatively thereto respectively, a manually controlled detent adapted selectively to anchor the sub-carriage relative to the frame and simultaneously to operate said latch mechanism to unlatch the sub-carriage from the main carriage, or to release the sub-carriage from the frame and to latch the sub-carriage to the main carriage for movement therewith, and means operable by said latch mechanism for opening said automatic switch when the latch mechanism is operated to release the sub-carriage from the main carriage.

2. A character repeating mechanism for a typewriter having on a frame a main carriage and a typing mechanism for the character to be repeated; comprising an electrically driven mechanism adapted when energized to operate said typing mechanism repetitiously, a circuit for energizing said electrically driven mechanism, an automatic switch in said circuit, a sub-carriage, a latch mechanism on the sub-carriage for attaching it to or detaching it from the main carriage for movement therewith or relatively thereto respectively, a manually controlled detent adapted selectively to anchor the sub-carriage relative to the frame and simultaneously to operate said latch mechanism to unlatch the sub-carriage from the main carriage, or to release the sub-carriage from the frame and to latch the sub-carriage to the main carriage for movement therewith, means operable by said latch mechanism for opening said automatic switch when the latch mechanism is operated to release the sub-carriage from the main carriage, a manual switch in said circuit, and elements on the sub-carriage engageable with the detent when the detent is in anchoring position automatically to anchor the sub-carriage relatively to the frame while releasing it from the main carriage and simultaneously to operate the latch mechanism to open said automatic switch.

3. A character repeating mechanism for a typewriter having on a frame a main carriage and a typing mechanism for the character to be repeated; comprising an electrically driven mechanism adapted when energized to operate said typing mechanism repetitiously, a circuit for energizing said electrically driven mechanism, a sub-carriage supported on but movable relatively to the main carriage, an automatic switch in said circuit and located on the carriage, a latch mechanism on the sub-carriage for attaching it to or detaching it from the main carriage for movement therewith or relatively thereto respectively, a manually controlled detent adapted selectively

11

to anchor the sub-carriage relative to the frame and simultaneously to operate said latch mechanism to unlatch the sub-carriage from the main carriage, or to release the sub-carriage from the frame and to latch the sub-carriage to the main carriage for movement therewith, and means operable by said latch mechanism in any position of either carriage for opening said automatic switch when the latch mechanism is operated to release the sub-carriage from the main carriage.

4. A character repeating mechanism for a typewriter having on a frame a main carriage and a typing mechanism for the character to be repeated; comprising an electrically driven mechanism adapted when energized to operate said typing mechanism repetitiously, a circuit for energizing said electrically driven mechanism, a sub-carriage supported on but movable relatively to the main carriage, an automatic switch in said circuit and located on the carriage, a latch mechanism on the sub-carriage for attaching it to or detaching it from the main carriage for movement therewith or relatively thereto respectively, a manually controlled detent adapted selectively to anchor the sub-carriage relative to the frame and simultaneously to operate said latch mechanism to unlatch the sub-carriage from the main carriage, or to release the sub-carriage from the frame and to latch the sub-carriage to the main carriage for movement therewith, means operable by said latch mechanism in any position of either carriage for opening said automatic switch when the latch mechanism is operated to release the sub-carriage from the main carriage, a manual switch in said circuit, and elements on the sub-carriage engageable with the detent when the detent is in anchoring position automatically to anchor the sub-carriage relatively to the frame while releasing it from the main carriage and simultaneously to operate the latch mechanism to open said automatic switch.

5. A character repeating mechanism for a typewriter having on a frame a main carriage and a typing mechanism for the character to be repeated; comprising an electrically driven mechanism adapted when energized to operate said typing mechanism repetitiously, a circuit for energizing said electrically driven mechanism, an automatic switch in said circuit, a sub-carriage with respect to which the main carriage is movable, a latch mechanism on the sub-carriage for attaching it to or detaching it from the main carriage for movement therewith or relatively thereto respectively, means operable by said latch mechanism for opening and closing said automatic switch, and a manually controlled detent adapted selectively to anchor the sub-carriage relatively to the frame and simultaneously to operate said latch mechanism to unlatch the sub-carriage from the main carriage while opening the automatic switch, or to release the sub-carriage from the frame and to latch the sub-carriage to the main carriage for movement therewith while closing said automatic switch.

6. A character repeating mechanism for a typewriter having on a frame a main carriage and a typing mechanism for the character to be repeated; comprising an electrically driven mechanism adapted when energized to operate said typing mechanism repetitiously, a circuit for energizing said electrically driven mechanism, an automatic switch in said circuit including an elongate member, a sub-carriage with respect to which the main carriage is movable in the direction of said elongate member, a latch mechanism

12

on the sub-carriage for attaching it to or detaching it from the main carriage for movement therewith or relatively thereto respectively, said latch mechanism cooperating with said elongate member to open and close said automatic switch, a manually controlled detent adapted selectively to anchor the sub-carriage relatively to the frame and simultaneously to operate said latch mechanism to unlatch the sub-carriage from the main carriage while said latch mechanism cooperates with said elongate member to open the automatic switch, or to release the sub-carriage from the frame and to latch the sub-carriage to the main carriage for movement therewith while said latch mechanism cooperates with said elongate member to close said automatic switch.

7. A repeater mechanism for a typewriter having on a frame a main carriage and a typing mechanism for a character to be repeated; an electrical mechanism adapted when energized to operate said typing mechanism repetitiously, a circuit for said electrical mechanism, a sub-carriage supported on but movable longitudinally relatively to the main carriage, a latch mechanism on the sub-carriage for connecting it to and disconnecting it from the main carriage, a switch operable by said latch mechanism to be opened only when the sub-carriage is disconnected from the main carriage, and manually operated latch control means normally biasing the latch mechanism to disconnect the sub-carriage from the main carriage and holding the sub-carriage in a fixed position relative to the main frame.

8. A repeater mechanism for a typewriter having on a frame a main carriage and a typing mechanism for a character to be repeated; an electrical mechanism adapted when energized to operate said typing mechanism repetitiously, a circuit for said electrical mechanism, a sub-carriage supported on but movable longitudinally relatively to the main carriage, a latch mechanism on the sub-carriage for connecting it to and disconnecting it from the main carriage, a switch operable by said latch mechanism to be opened only when the sub-carriage is disconnected from the main carriage, and manually operated latch control apparatus normally biasing the latch mechanism to disconnect the sub-carriage from the main carriage and holding the sub-carriage in a fixed position relative to the control apparatus, said control apparatus being manually operable to release the sub-carriage from the control apparatus and connect it to the main carriage, said sub-carriage including elements reengaging the latch control apparatus to hold the sub-carriage when the sub-carriage arrives at a position adjacent thereto.

9. A repeater mechanism for a typewriter having on a frame a main carriage and a typing mechanism for a character to be repeated; a sub-carriage, a manually releasable detent for holding the sub-carriage in a fixed position relative to the main frame, a latch mechanism on the sub-carriage operated by the detent when the sub-carriage is detained and adapted to disconnect the sub-carriage from the main carriage, said detent when manually operated to release the sub-carriage for movement relative to the main frame also releasing said latch mechanism to connect the sub-carriage to the main carriage, and elements associated with the sub-carriage whereby the detent is caused again to detain the sub-carriage and operate the latch mechanism to release said sub-carriage from the main car-

riage when the sub-carriage arrives with the main carriage at a location adjacent to said detent.

10. A character repeating mechanism for a typewriter having on a frame a main carriage and a typing mechanism for the character to be repeated; comprising an electrically driven mechanism adapted when energized to operate said typing mechanism repetitiously, a circuit for energizing said electrically driven mechanism, an automatic switch in said circuit, a sub-carriage, a manually releasable detent mechanism adapted normally to anchor the sub-carriage to the frame and release it from the main carriage, said detent mechanism when manually operated releasing the sub-carriage from the frame and connecting it with the main carriage for movement therewith, and switch-operating means associated with the detent mechanism for closing said automatic switch as long as the sub-carriage is connected with the main carriage but adapted to open said switch whenever the sub-carriage is released from the main carriage.

11. A character repeating mechanism for a typewriter having on a frame a main carriage and a typing mechanism for the character to be repeated; comprising an electrically driven mechanism adapted when energized to operate said typing mechanism repetitiously, a circuit for energizing said electrically driven mechanism, an automatic switch in said circuit, a sub-carriage, a manually releasable detent mechanism adapted normally to anchor the sub-carriage to the frame and release it from the main carriage, said detent mechanism when manually operated releasing the sub-carriage from the frame and connecting it with the main carriage for movement therewith, switch-operating means associated with the detent mechanism for closing said automatic switch as long as the sub-carriage is connected with the main carriage but adapted to open said switch whenever the sub-carriage is released from the main carriage, and a mechanism on the sub-carriage adapted automatically to place the detent mechanism in operative position to disconnect the sub-carriage from the main carriage whenever the sub-carriage reaches a predetermined location relative to the frame.

12. A character repeating mechanism for a typewriter having on a frame a main carriage and a typing mechanism for a character to be repeated; comprising an electrically driven mechanism adapted when energized to operate said typing mechanism repetitiously, a circuit for energizing said electrically driven mechanism, an automatic switch in said circuit, a sub-carriage, a manually releasable detent mechanism adapted normally to anchor the sub-carriage to the frame and release it from the main carriage, said detent mechanism when manually operated releasing the sub-carriage from the frame and connecting it with the main carriage for movement therewith, switch-operating means associated with the detent mechanism for closing said automatic switch as long as the sub-carriage is connected with the main carriage but adapted to open said switch whenever the sub-carriage is released from the main carriage, a mechanism on the sub-carriage adapted automatically to place the detent mechanism in operative position to disconnect the sub-carriage from the main carriage whenever the sub-carriage reaches a predetermined location relative to the frame.

and adapted to open said automatic switch, and a second normally open manually closable control switch in said circuit.

13. A character repeating mechanism for a typewriter having on a frame a main carriage and a typing mechanism for a character to be repeated; comprising an electrically driven mechanism adapted when energized to operate said typing mechanism repetitiously, a circuit for energizing said electrically driven mechanism, an automatic switch in said circuit, a sub-carriage, a manually releasable detent mechanism adapted normally to anchor the sub-carriage to the frame and release it from the main carriage, said detent mechanism when manually operated releasing the sub-carriage from the frame and connecting it with the main carriage for movement therewith, switch-operating means associated with the detent mechanism for closing said automatic switch as long as the sub-carriage is connected with the main carriage but adapted to open said switch whenever the sub-carriage is released from the main carriage, a mechanism on the sub-carriage adapted automatically to place the detent mechanism in operative position to disconnect the sub-carriage from the main carriage whenever the sub-carriage reaches a predetermined location relative to the frame and adapted to open said automatic switch, a second normally open manually closable control switch in said circuit, a third normally closed control switch in said circuit, and an element adapted automatically to open said third switch when the main carriage reaches the end of a predetermined travel.

14. A character repeating mechanism for a typewriter having on a frame a main carriage and a typing mechanism for a character to be repeated; comprising an electrically driven mechanism adapted when energized to operate said typing mechanism repetitiously, a circuit for energizing said electrically driven mechanism, an automatic switch in said circuit, a sub-carriage, a manually releasable detent mechanism adapted normally to anchor the sub-carriage to the frame and release it from the main carriage, said detent mechanism when manually operated releasing the sub-carriage from the frame and connecting it with the main carriage for movement therewith, switch-operating means associated with the detent mechanism for closing said automatic switch as long as the sub-carriage is connected with the main carriage but adapted to open said switch whenever the sub-carriage is released from the main carriage, a mechanism on the sub-carriage adapted automatically to place the detent mechanism in operative position to disconnect the sub-carriage from the main carriage whenever the sub-carriage reaches a predetermined location relative to the frame and adapted to open said automatic switch, a second normally open manually closable control switch in said circuit, a third normally closed control switch in said circuit, and an adjustable element on the main carriage adapted automatically to open said third switch when the main carriage has covered a predetermined travel.

15. A character repeating mechanism for a typewriter having on a frame a main carriage and a typing mechanism for the character to be repeated; comprising a driving mechanism adapted selectively to operate said typing mechanism repetitiously, a control circuit for said driving mechanism, an automatic switch in said

circuit, a sub-carriage, a latch mechanism on the sub-carriage for attaching it to or detaching it from the main carriage for movement therewith or relatively thereto respectively, a manually controlled detent adapted selectively to anchor the sub-carriage relative to the frame and simultaneously to operate said latch mechanism to unlatch the sub-carriage from the main carriage, or to release the sub-carriage from the frame and to latch the sub-carriage to the main carriage for movement therewith, and means operable by said latch mechanism for opening said automatic switch when the latch mechanism is operated to release the sub-carriage from the main carriage.

16. A character repeating mechanism for a typewriter having on a frame a main carriage and a typing mechanism for the character to be repeated; comprising a driving mechanism adapted selectively to operate said typing mechanism repetitiously, a control circuit for said driving mechanism, an automatic switch in said circuit, a sub-carriage, a latch mechanism on the sub-carriage for attaching it to or detaching it from the main carriage for movement therewith or relatively thereto respectively, a manually controlled detent adapted selectively to anchor the sub-carriage relative to the frame and simultaneously to operate said latch mechanism to unlatch the sub-carriage from the main carriage, or to release the sub-carriage from the frame and to latch the sub-carriage to the main carriage for movement therewith, means operable by said latch mechanism for opening said automatic switch when the latch mechanism is operated to release the sub-carriage from the main carriage, a manual switch in said circuit, and elements on the sub-carriage engageable with the detent when the detent is in anchoring position automatically to anchor the sub-carriage relatively to the frame while releasing it from the main carriage and simultaneously to operate the latch mechanism to open said automatic switch.

17. A character repeating mechanism for a typewriter having on a frame a main carriage and a typing mechanism for the character to be repeated; comprising a driving mechanism adapted selectively to operate said typing mechanism repetitiously, a control circuit for said driving mechanism, a sub-carriage supported on but movable relatively to the main carriage, an automatic switch in said circuit, a latch mechanism on the sub-carriage for attaching it to or detaching it from the main carriage for movement therewith or relatively thereto respectively, a manually controlled detent adapted selectively to anchor the sub-carriage relative to the frame and simultaneously to operate said latch mechanism to unlatch the sub-carriage from the main carriage, or to release the sub-carriage from the frame and to latch the sub-carriage to the main carriage for movement therewith, and means operable by said latch mechanism in any position of either carriage for opening said automatic switch when the latch mechanism is operated to release the sub-carriage from the main carriage.

18. A character repeating mechanism for a typewriter having on a frame a main carriage and a typing mechanism for the character to be repeated; comprising a driving mechanism adapted selectively to operate said typing mechanism repetitiously, a control circuit for said driving mechanism, a sub-carriage supported on but movable relatively to the main carriage, an automatic switch in said circuit, a latch mechanism

on the sub-carriage for attaching it to or detaching it from the main carriage for movement therewith or relatively thereto respectively, a manually controlled detent adapted selectively to anchor the sub-carriage relative to the frame and simultaneously to operate said latch mechanism to unlatch the sub-carriage from the main carriage, or to release the sub-carriage from the frame and to latch the sub-carriage to the main carriage for movement therewith, means operable by said latch mechanism in any position of either carriage for opening said automatic switch when the latch mechanism is operated to release the sub-carriage from the main carriage, a manual switch in said circuit, and elements on the sub-carriage engageable with the detent when the detent is in anchoring position automatically to anchor the sub-carriage relatively to the frame while releasing it from the main carriage and simultaneously to operate the latch mechanism to open said automatic switch.

19. A character repeating mechanism for a typewriter having on a frame a main carriage and a typing mechanism for the character to be repeated; comprising a driving mechanism adapted selectively to operate said typing mechanism repetitiously, a control circuit for said driving mechanism, an automatic switch in said circuit, a sub-carriage with respect to which the main carriage is movable, a latch mechanism on the sub-carriage for attaching it to or detaching it from the main carriage for movement therewith or relatively thereto respectively, means operable by said latch mechanism for opening said automatic switch when the latch mechanism is operated to release the sub-carriage from the main carriage, and closing said automatic switch, and a manually controlled detent adapted selectively to anchor the sub-carriage relatively to the frame and simultaneously to operate said latch mechanism to unlatch the sub-carriage from the main carriage while opening the automatic switch, or to release the sub-carriage from the frame and to latch the sub-carriage to the main carriage for movement therewith while closing said automatic switch.

20. A character repeating mechanism for a typewriter having on a frame a main carriage and a typing mechanism for the character to be repeated; comprising a driving mechanism adapted selectively to operate said typing mechanism repetitiously, a control circuit for said driving mechanism, an automatic switch in said circuit including an elongate member, a sub-carriage with respect to which the main carriage is movable in the direction of said elongate member, a latch mechanism on the sub-carriage for attaching it to or detaching it from the main carriage for movement therewith or relatively thereto respectively, said latch mechanism cooperating with said elongate member to open and close said automatic switch, a manually controlled detent adapted selectively to anchor the sub-carriage relatively to the frame and simultaneously to operate said latch mechanism to unlatch the sub-carriage from the main carriage while said latch mechanism cooperates with said elongate member to open the automatic switch, or to release the sub-carriage from the frame and to latch the sub-carriage to the main carriage for movement therewith while said latch mechanism cooperates with said elongate member to close said automatic switch.

21. A character repeating mechanism for a typewriter having on a frame a main carriage and a typing mechanism for the character to be repeated; comprising a driving mechanism

adapted selectively to operate said typing mechanism repetitiously, a control circuit for said driving mechanism, an automatic switch in said circuit, a sub-carriage, a manually releasable detent mechanism adapted normally to anchor the sub-carriage to the frame and release it from the main carriage, said detent mechanism when manually operated releasing the sub-carriage from the frame and connecting it with the main carriage for movement therewith, switch-operating means associated with the detent mechanism for closing said automatic switch as long as the sub-carriage is connected with the main carriage but adapted to open said switch whenever the sub-carriage is released from the main carriage, a mechanism on the sub-carriage adapted automatically to place the detent mechanism in operative position to disconnect the sub-carriage from the main carriage whenever the sub-carriage reaches a predetermined location relative to the frame and adapted to open said automatic switch, a second normally open manually closable control switch in said circuit, a third normally closed control switch in said circuit, and an adjustable element on the main carriage adapted automatically to open said third switch when the main carriage has covered a predetermined travel.

22. In a typewriter having a movable carriage and a typing key mechanism cooperating with said carriage, a repeating mechanism associated with at least one typing key of said typing mecha-

- nism, means for initiating the operation of said repeating mechanism, a mechanism responsive to the travel of the carriage to a predetermined point adapted automatically to discontinue the operation of the repeating mechanism, and apparatus responsive to preliminary carriage movement for automatically adjusting said discontinuing mechanism to determine the position of said desired point of discontinuation.
- 10 23. In a typewriter having a movable carriage and a typing key mechanism cooperating with said carriage, a repeating mechanism associated with at least one typing key of said typing mechanism, a clutch for initiating the operation of
- 15 16 said repeating mechanism, a mechanism responsive to the travel of the carriage to a desired point adapted automatically to open the clutch to discontinue the operation of the repeating mechanism, and apparatus responsive to preliminary carriage movement for adjusting said discontinuing mechanism to determine the position of said desired point of discontinuation.
